UNITED STATES PATENT OFFICE.

WILLIAM D. SHONEFELT AND RICHARD VAUGHAN, OF SACRAMENTO, CALIFORNIA.

COLLAPSIBLE BOILER-PLUG.

No. 927,688.

Specification of Letters Patent.

Patented July 13, 1909.

Application filed April 20, 1909. Serial No. 491,175.

To all whom it may concern:

Be it known that we, WILLIAM D. SHONEFELT and RICHARD VAUGHAN, both of Sacramento, in the county of Sacramento and State of California, have jointly invented a certain new and useful Improvement in Collapsible Boiler-Plugs, of which improvement the following is a specification.

Our invention relates to means for preventing the burning or explosion of locomotive and other steam boilers, which frequently results from failure to maintain the proper water level above the crown sheets thereof and the consequent overheating of the crown sheets.

The object of our invention is to provide an appliance of such character which shall be simple and inexpensive in its construction; of ready applicability in steam boilers having water wall inclosed fireboxes of any of the ordinary forms; and positive, sensitive, and reliable in operation, by reason of the absence of any parts requiring shearing strain for their separation or so disposed as to release after separation.

The improvement claimed is hereinafter fully set forth.

In the accompanying drawing: Figure 1 is a plan or top view of a collapsible boiler plug embodying our invention; and; Fig. 2, a vertical central section through the same, as fixed in operative position in the crown sheet of a steam boiler.

In the practice of our invention, we provide a collapsible boiler plug comprising the following members, viz: First, a hollow or tubular body, 1, of metal, as iron or steel, which is open at its lower end and closed at its upper end, except as to a central opening, 1^a, and is provided with an external screw thread, 1^b, throughout a portion of its length, by which it is connected to a corresponding internal screw thread, tapped in a hole which is drilled in the crown sheet, 4, of a locomotive or other steam boiler, to receive the plug. Second, a disk or plate, 2, usually made of brass, which is of slightly less diameter than the bore of the body, 1, and is located therein adjacent to its top. The disk, 2, closes the opening in the top of the body, and is preferably, as shown, provided with a central boss or projection, 2^a, on its top, fitting neatly in said opening and extending a sufficient distance to be substantially flush with the upper surface of the top of the body, so as to prevent said opening from becoming

choked by deposits of scale. Third, a seal, 3, of tin or other metal fusible at a comparatively low temperature, which is interposed between the inner surface of the top of the body and the top of the disk, 2, and serves to connect said parts by being fused thereto. The seal being entirely separated from the space above the crown sheet, is exempt from liability to become corroded and is also protected from the direct action of the heat in the firebox, without which protection the fusing properties of the plug would be so impaired as to destroy its reliability in time of need. A characteristic feature of the seal is that it is not connected to the body and disk by screw threads or other interlocking projections, and consequently does not involve the exertion of shearing strain in its separation therefrom. We therefore designate it as "plane surfaced," meaning thereby that its surfaces are without interlocking projections. It will, however, be obvious to those skilled in the art, that so long as the seal is not interlocked with the adjoining members, the specific form of its surfaces, *i. e.*, whether the same are portions of flat or of curved planes, is not of the essence of our invention.

In the normal operation of the boiler, that is to say, when the water level therein is maintained at a proper height above the crown sheet, 4, the seal, 3, is protected, by the comparatively cool water surrounding the body of the plug, from being fused by the heat in the firebox, as well as protected by being set at a higher level than the crown sheet, at the top of the space within the body of the plug, which acts in the manner of a cooling chamber. When the level of the water is allowed, by inadvertence or by failure of the feed mechanism, to fall below the normal and safe height above the crown sheet, 4, the heat in the firebox will soften and partially fuse the seal, 3, and the plug will collapse, its disk, 2, being separated from its connection with the body, 1, without the possibility of becoming resealed, and blown into the firebox by the pressure of the steam above it. The escape of steam through the opening, 1^a, in the top of the plug, will give warning to the engineer, and dampen or extinguish, the fire, thereby preventing the burning of the sheets or the explosion of the boiler which would otherwise be liable to result.

We claim as our invention and desire to secure by Letters Patent:

1. In a collapsible plug for steam boiler sheets, the combination of a hollow or tubular body, having an open lower end and an opening in its upper end, a disk or plate located within the tubular body, in position to close the upper opening thereof, and a plane surfaced seal formed of metal fusible at comparatively low temperature, and interposed between and connecting the disk or plate and the top of the body.
2. In a collapsible plug for steam boiler sheets, the combination of a hollow or tubular body having an open lower end and an opening in its upper end, a disk or plate located within the tubular body, in position to close the upper opening thereof, and a flat plane surfaced seal formed of metal fusible at comparatively low temperature, and interposed between and connecting the disk or plate

and the top of the body without interlocking engagement with either.

3. In a collapsible plug for steam boiler sheets, the combination of a hollow or tubular body having an open lower end and an opening in its upper end, a disk or plate located within the tubular body and having a boss or projection on its top fitting in and closing the upper opening of the body, and a seal, formed of metal fusible at comparatively low temperature, and interposed between and connecting the disk or plate and the top of the body, around the projection of the disk or plate.

WILLIAM D. SHONEFELT.
RICHARD VAUGHAN.
